TOILET PAPER ROLL HOLDER

Charles Joseph Leveque, Goose Creek, Tex.

Application January 22, 1942, Serial No. 427,815

3 Claims. (CL 242—55.3)

The present invention relates to new and useful improvements in toilet paper roll holders, and has for its primary object to provide, in a manner as hereinafter set forth, a device of this character which is adapted to contain a reserve stock or supply of paper in position for convenient use.

Another very important object of the invention is to provide a holder of the aforementioned character comprising novel means for removing the rolls one at a time from the reserve stock as they are needed and for supporting said rolls in a manner to facilitate the removal of the paper therefrom.

Other objects of the invention are to provide a toilet paper roll holder of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a toilet paper roll holder constructed in accordance with the present invention.

Figure 2 is a view in front elevation of the lower portion of the device.

Figure 3 is a vertical sectional view, taken substantially on the line 3—3 of Figure 2.

Figure 4 is a detail view of the roll withdrawing and supporting tongs.

Figure 5 is a cross-sectional view, taken substantially on the line 5—5 of Figure 4.

Referring now to the drawings in detail, it will be seen that the embodiment of the invention which has been illustrated comprises a magazine of suitable material which is designated generally by reference numeral 1. The magazine 1 is for the reception of a stack or column of rolls of toilet paper 2.

The magazine 1 is adapted to be secured in any suitable manner in a convenient location on a wall or other support and said magazine comprises a back 3, side walls 4, a front 5 and a rearwardly inclined bottom 6, said bottom being located above the lower ends of the back 3 and the side walls 4. The front 5 terminates, at its lower end, a substantial distance above the bottom 6 for providing a sufficiently large opening for the

discharge of the rolls 2. This is shown to advantage in Figure 3 of the drawings.

Above the bottom 6 the side walls 4 have extending thereinto from their front edges recesses 7 the purpose of which will be presently set forth. Extending into the side walls 4 from the front edges thereof below the bottom 6 are notches 7'. The notches 7' are formed to provide horizontal shoulders 8, the purpose of which will also be presently set forth.

Journalized in the side walls 4 immediately below the front edge of the bottom 6 and above the shoulders 8 is a rod or shaft 9. Fixed on the shaft 9 is a bar 10. A pair of tongs 11 is mounted on the bar 10. The tongs 11 comprise a pair of angular arms 12 having one end portion pivotally secured at 13 to the bar 10. Meshed gear segments 14 on the pivoted ends of the arms 12 operatively connect said arms together for swinging movement in unison on the bar 10. Projecting inwardly from the free end portions of the arms 12 are fingers constituting spindles 15 which are engageable in the usual centrally located openings 16 in the paper rolls 2. These end portions of the arms 12 are further provided with finger openings 17 for convenient operation.

It is believed that the operation of the device will be readily apparent from a consideration of the foregoing. Briefly, the bottom 6 supports the stack of paper rolls 2 in the magazine 1, from which rolls the usual wrappers have been removed before said magazine is loaded. To remove the lowermost roll 2, the tongs 11 are opened and swung upwardly and rearwardly into the recesses 7, the spindles 15 clearing the ends of said lowermost roll. The tongs 11 are then closed for engaging the fingers 15 in the openings 16 in the lowermost roll 2. This is illustrated in Figures 1 and 2 of the drawings. Operation of either of the arms 12 actuates the other of said arms. The tongs 11 are then swung forwardly and downwardly in a manner to pull the lowermost roll 2 out of the magazine 1. When this occurs the rolls remaining in the magazine drop downwardly by gravity and are supported by the bottom 6. When the tongs 11 are swung outwardly, the bar 10 enters the notches 7' and engages beneath the shoulders 8 for supporting said tongs in a substantially horizontal position with a roll of paper therein, as suggested in broken lines in Figure 1 of the drawings. The roll of paper thus supported is adapted to rotate or turn freely on the fingers or spindles 15. When another roll of paper is desired the foregoing operation is repeated. When the tongs 11 are in

extended position the portions 18 of the arms 12 abut the inner portions of the walls of the notches 7 for positively preventing opening of said arms.

It is believed that the many advantages of a toilet paper roll holder constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A toilet paper roll holder of the character described comprising a magazine for the reception of a stack of paper rolls, said magazine having a discharge opening therein for the rolls, and a pair of tongs mounted for swinging movement on the magazine, said tongs being engageable in the lowermost roll for withdrawing same from the magazine and for rotatably supporting said lowermost roll exteriorly of said magazine.

2. A toilet paper roll holder comprising a maga-

zine for the reception of a stack of paper rolls, a member mounted for swinging movement on the magazine, said magazine having a discharge opening therein adjacent said member, and a pair of tongs mounted on the member and engageable in the lowermost roll for withdrawing same from the magazine and for rotatably supporting said lowermost roll exteriorly of said magazine.

3. A toilet paper roll holder of the character described comprising a magazine for the reception of a stack of rolls of paper, said magazine having a discharge opening for said rolls in its lower portion, a bar mounted for swinging movement on the magazine below the discharge opening, a pair of tongs mounted on said bar, said tongs including angular arms operatively connected together, and spindles on said arms engageable in the lowermost roll for withdrawing said lowermost roll from the magazine, and means on the magazine engageable by the bar for supporting the arms in extended position.

CHARLES JOSEPH LEVEQUE.
